UNITED STATES PATENT OFFICE.

JOHN WEBER, OF SCHENECTADY, NEW YORK, ASSIGNOR TO WEBER ELECTRIC COMPANY, OF SCHENECTADY, NEW YORK, A CORPORATION OF NEW YORK.

CASE FOR INCANDESCENT-ELECTRIC-LAMP SOCKETS.

1,234,985.

Specification of Letters Patent.

Patented July 31, 1917.

Application filed September 3, 1912. Serial No. 718,173.

To all whom it may concern:

Be it known that I, JOHN WEBER, a citizen of the United States, residing at Schenectady, county of Schenectady, and State 5 of New York, have invented certain new and useful Improvements in Cases for Incandescent-Electric-Lamp Sockets, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view partly in side elevation and partly in central vertical section of an incandescent electric lamp-socket case containing my invention.

Fig. 2 is a view partly in side elevation and partly in vertical cross-section of the apertured locking ring detached.

Fig. 3 is a top plan view of said locking ring.

Fig. 4 is a view partly in side elevation and partly in vertical cross-section of the cap detached.

Fig. 5 is a view in side elevation of a broken-away portion of the sleeve.

Fig. 6 is a vertical cross-section of a broken-away portion of the interlocked cap and sleeve taken through the interengaging 35 mechanism which locks the parts against relative rotation.

Fig. 7 is a top plan view of the sleeve detached.

Fig. 1 is drawn on a smaller scale than the 40 other figures, all being drawn on an enlarged scale.

Certain objects of the invention are to facilitate the insertion of the sleeve within the cap of the socket; and to securely lock the 45 sleeve and cap together both against separation and against rotation in numerous relative rotary positions.

Other objects will appear in connection 50 with the following description.

Referring to the drawings wherein the invention is shown in preferred form, 1, is the sleeve and, 2, is the cap of the case both

preferably made of sheet-metal, the sleeve being shown provided with the usual key-slot, 3.

55

The cap is adapted to telescopically receive and fit the inner end of the sleeve which has near its inner end a plurality of outward projections or catches, 4, which may be formed in any known manner, but 60 which I prefer to form by transversely slitting the wall of the sleeve and displacing outwardly a portion of the sleeve-wall on the inner side of said slit to form an inclined projection terminating in a cut-metal 65 edge.

The sleeve also has near its inner end at least one outward projection, 5, which may be formed in any known manner, but which I prefer to form by outwardly displacing 70 a narrow strip of the wall of the sleeve between two vertical slits, whereby said projection presents cut-metal edges on its opposite sides.

Located within the flange, 6, of the cap 75 is an annular sheet-metal member or ring, 7, concealed therewithin and secured therein between the introverted edge, 8, of the flange, 6, and a plurality of internal projections, 9, overhanging portions of said ring, 7.

80

I have shown the upper end of the ring, 7, inwardly offset at, 10, and terminating in an upwardly disposed cut-metal edge, 11, which by reason of said offset, 10, is set in slightly from the wall of the cap-flange, 6, 85 leaving a free space therebetween, said cut-metal edge, 11, being adapted to engage the cut-metal edges of the projections, 4, on the sleeve when the cap and sleeve are telescopically assembled to lock the parts against 90 separation.

The free space thus provided between the cap-flange and the cut-metal edge, 11, serves to freely receive the ends of the projections, 4, permitting them to substantially overhang 95 said cut-metal edge to form a most secure lock.

The ring, 7, is also provided with a series of openings, 12, adapted respectively to receive the projection, 5, on the sleeve when 100 the cap and sleeve are telescopically assembled, to lock them against relative rotation.

The openings, 12, may be formed in any known manner, but I prefer to form them

as rectangular notches alternating with rectangular teeth on the edge of the ring, 7, as shown.

The openings thus present oppositely disposed cut-metal edges to the cut-metal edges of the projection, 5, on the sleeve.

The internal projections, 9, which hold the ring, 7, in place within the cap are preferably formed by slitting the wall of the 10 cap and inwardly displacing the metal adjacent to said slit to adapt the same to overhang the shoulder formed on the ring by the offset, 10, as clearly shown in Fig. 4.

The ring, 7, may be secured within the 15 cap in any known manner.

I prefer, however, to slightly upset the in-turned edge of the flange, 6, into some or all of the notch-openings, 12, as shown at, 13, in Fig. 4, whereby said ring, 7, is secured 20 against rotation within the cap.

The projection, 5, is preferably formed with an inclined or beveled end over which the in-turned edge of the cap-flange can freely ride in assembling the cap and sleeve.

25 The cap and sleeve can be telescopically assembled by a straight-line movement or by a straight-line movement accompanied by a slight rotative movement.

In either case, the catches, 4, will at once 30 interlock with the edge, 11, of the ring, 7, and by a slight rotative movement in assembling, or afterward, the projection, 5, will be seated in one of the notches, 12, even though it should not be at first properly 35 alined with said notch.

This slight rotative movement, after the parts are assembled to interlock against separation, is limited to the width of a single tooth on the ring, 7, and is negligible in the 40 use of the device.

By having the upper end of the ring, 7, inwardly offset, the space inclosed by said offset end is of less diameter than the space inclosed by the in-turned edge, 8, of the 45 flange, 6, which edge is inturned but slightly and to the extent of only the thickness of the sheet-metal forming the ring, 7.

I am thus able to inwardly offset the upper end of the sleeve, 1, as shown at, 15, 50 to provide the sleeve with a contracted inner end adapted to fit within the offset end of the ring, 7, the catches, 4, being formed on said contracted portion of said sleeve, 1, while the projection, 5, is formed on a part 55 of the sleeve which is of full diameter and adapted to fit within the inturned flange, 8, and within the apertured portion of the ring, 7, as clearly shown in Fig. 6.

Substantial clearance is thus provided for 60 between the contracted end of the sleeve and the opening into the cap which greatly facilitates the insertion of the sleeve within the cap.

By thus offsetting the sleeve I am able to 65 permit it to project within the dome, 17, of

the cap, if desired, as shown at, 16, in Fig. 6, wherein I have shown contained within the case a broken-away part of the interior mechanism consisting of the insulating lining, 18, and insulating support, 19, for the 70 terminals with which the inleading wires (not shown) are connected, one of said terminals, 29, being shown provided with a binding screw, 20.

Said interior mechanism is capable of a 75 slight upward movement within the dome, 17, without preventing the case-members from being properly assembled and interlocked.

By having the body of the sleeve of larger 80 diameter than its innermost end, I provide a free air-space, 21, between the insulating lining, 18, and the sleeve opposite the terminals or binding-screws, if the insulating lining is employed; and if it is not employed, 85 I nevertheless increase the distance or air-space between the terminals or binding-screws and the sleeve, thus adding to the safety of the device.

The binding-screw is located within a peripheral notch in the insulating support, 19.

What I claim as new and desire to secure by Letters Patent is—

1. In an electric lamp-socket case, and in combination, a sleeve; and a cap adapted to 95 telescopically receive said sleeve, said cap and sleeve having interengaging means to prevent separation comprising in part a projection on said sleeve, and a sheet-metal member contained within the cap having a 100 cut-metal edge adapted to engage said projection on the sleeve, said cut-metal edge being separated from the outer wall of the cap by a free space adapted to receive the end of said projection.

2. In an electric lamp-socket case, and in combination, a sleeve; and a cap adapted to 110 telescopically receive said sleeve, said cap and sleeve having interengaging means to prevent separation comprising in part projections on said sleeve, and an annular metal member contained within the cap having a 115 continuous cut-metal edge adapted to engage said projections on the sleeve, said cut-metal edge being separated from the outer wall of the cap by a wholly surrounding free space adapted to receive the ends of said projections.

3. In an electric lamp-socket case, and in combination, a sleeve; and a cap adapted to 120 telescopically receive said sleeve, said cap and sleeve having interengaging means to prevent separation comprising in part projections on said sleeve, and an annular sheet-metal member contained within the cap, said 125 projections and said annular member having mutually abutting cut-metal edges, the cut-metal edge of said annular member being bent away from the outer wall of the cap forming a wholly surrounding free 130

space into which the ends of said projections are adapted to project.

4. In an electric lamp-socket case, and in combination, a sleeve; and a cap adapted to 5 telescopically receive said sleeve, said cap and sleeve having interengaging means comprising in part projections on said sleeve, and an annular sheet-metal member contained within said cap having a continuous 10 cut-metal edge adapted to engage certain of said projections on the sleeve and provided with openings adapted to engage another of said projections on the sleeve.

5. In an electric lamp-socket case, and in 15 combination, a sleeve having projections; a cap adapted to telescopically receive said sleeve; an annular sheet-metal member within said cap with its inner end inwardly offset and terminating in a continuous cut- 20 metal edge adapted to engage certain of said projections on the sleeve, said annular member being provided with openings adapted to engage another of said projections on the sleeve.

25 6. In an electric lamp-socket case, and in combination, a sheet-metal sleeve having portions of its wall displaced to form inclined projections terminating in cut-metal ends and another portion of its wall displaced to form a projection having cut-metal 30 sides; and a cap adapted to telescopically receive said sleeve, said cap having contained therewithin an annular sheet-metal member having a continuous cut-metal edge 35 adapted to engage the cut-metal ends of said projections on the sleeve and being provided with a series of openings having oppositely faced cut-metal edges respectively adapted to engage the cut-metal sides of said 40 projection on the sleeve.

7. An electric lamp-socket-case comprising in combination, a sleeve having an end of smaller diameter than its body portion; and a cap adapted to telescopically receive 45 said end of the sleeve, said cap having an end portion with an interior surface opposite, and corresponding in diameter with, the body portion of the sleeve, and a separate member mounted within the cap having a bearing surface opposite, and corresponding in diameter with, said end of the sleeve of smaller diameter than the body of the sleeve, said sleeve having means cooperative with said separate member to prevent separation of the cap and sleeve.

50 8. In an electric lamp-socket case, and in combination, a sleeve having a contracted end; and a cap adapted to telescopically receive said sleeve and to fit a portion thereof 55 of full diameter, said cap having a contained member adapted to receive and fit the contracted end of the sleeve, said cap and a portion of said sleeve of full diameter hav-

ing interengaging means to prevent relative rotation and said contained member and the 65 contracted end of said sleeve having interengaging means to prevent separation.

9. In an electric lamp-socket case, and in combination, a sleeve having a contracted end and having projections on said contracted end and a projection on a portion of the sleeve of full diameter; and a cap adapted to telescopically receive said sleeve, said cap having a contained annular member inwardly offset at its inner end to fit the 75 contracted end of said sleeve and terminating in a continuous cut-metal edge adapted to engage the projections on the contacted end of the sleeve, said annular member having an apertured portion 80 adapted to fit said portion of the sleeve of full diameter and to engage the projection thereon.

10. In an electric lamp-socket, and in combination, interior mechanism comprising 85 in part an insulating support and a wire-connection terminal mounted upon the periphery of said support; a sleeve inclosing said interior mechanism having its inner end of a diameter adapted to closely fit said insulating support and having a portion of larger diameter opposite said terminal; and a cap adapted to telescopically receive said 90 sleeve.

11. An electric lamp-socket-case comprising in combination a pair of case-members one adapted to telescopically receive the other, the inner of said members having a plurality of exterior circumferential bearing surfaces of different diameters, and the 100 outer member having a plurality of interior circumferential bearing surfaces corresponding in diameter with, and adapted to fit respectively, said bearing surfaces on the inner member.

105 12. A case for incandescent electric lamp-sockets comprising in combination, a sleeve having an end portion of smaller diameter than its body portion, and a cap adapted to telescopically receive said end of the sleeve, 110 said cap having an interior surface opposite, and corresponding in diameter with, the body portion of the sleeve, and another interior surface opposite, and corresponding in diameter with, said end portion of the 115 sleeve of smaller diameter than the body of the sleeve, said sleeve having means cooperative with said member to prevent separation of the cap and sleeve.

In testimony whereof, I have hereunto set 120 my hand this 27th day of August, 1912.

JOHN WEBER.
